UNITED STATES PATENT OFFICE.

GEORGE T. BREEN, OF NEW ROCHELLE, NEW YORK, ASSIGNOR TO HERRING-HALL-MARVIN SAFE COMPANY, OF NEW YORK, N. Y., A CORPORATION OF NEW YORK.

CHUTE.

Application filed February 5, 1926. Serial No. 86,305.

My invention relates to chutes for safes, and more particularly relates to automatic locking mechanisms for such chutes which shall be burglar resisting and are devised for use in bank equipment to enable customers of the bank safely to deposit from the street after banking hours money or other valuables properly secured in individual bags or containers. Such containers are thereafter carried automatically through my improved form of chute into the subjacent bank vault or night safe located in the cellar of the bank building adjacent and below the street level for safe keeping until the next day.

The objects of my invention are, among other things, to provide a simple yet thoroughly effective chute and automatic locking devices therefor by which the different customers of the bank may have ready access to the outer chute door and receiving hopper arranged in the side-walls of the bank building at a convenient distance above the street level so as to deposit their individual containers for money or other valuables within the hopper by which such containers are thereafter allowed to fall by gravity through the chute into the night safe or vault from which the proper representatives of the bank may remove same from time to time, and particularly on such occasions when the customers have deposited their containers in the chute after banking hours to be received and opened by the bank on the following morning.

A further object and feature of my invention is to equip this chute with successive automatic locking devices effectively safeguarding the passageway through the chute so that it would be impossible to withdraw any of such money containers from the receiving vault after the customer has once deposited his container in the hopper and closed the entrance door opening in the bank side wall, by embodying in the chute structure a flexible finger-trap and an automatically operated sliding door which will act to preclude burglars from lifting any of the money containers upwardly through the chute once they had been deposited in the bank vault or night safe. In other words I have devised an improved automatic one-way chute provided with locking devices and traps, each automatically actuated, which

effectively prohibit any removal of the money containers by unauthorized persons attempting to tamper with or destroy the chute itself or any of its operating parts.

With these and other objects in view the invention also comprises the novel construction and arrangement of the operating parts shown and hereinafter to be described as one embodiment of my invention, and then particularly pointed out in the appended claims.

In the drawings, Fig. 1 is a side elevation partly in section of the side walls and cellar of a bank building having my improved chute and automatic locking devices installed therein;

Fig. 2 shows enlarged sectional views of parts shown in Fig. 1;

Fig. 3 is a perspective view of the chute head and entrance door;

Fig. 4 is an enlarged view showing the flexible finger-trap taken on the line 4-4 of Fig. 2;

Fig. 5 is a detail perspective view of one of the trap fingers;

Fig. 6 is a detailed sectional elevation showing the slide door closed at the base of the chute;

Fig. 7 is a detail view of the parts shown in Fig. 6; and

Fig. 8 is a detail sectional view of the receiving hopper and the coacting back plate of the housing comprising the chute head in a modified form.

Similar numerals refer to similar parts throughout the several figures.

Referring to Fig. 1, the cellar floor 9 and cellar wall 10 of the bank building enclose the safe or vault 11, having the inner compartment 12 closed by the hinged door 13 of any suitable construction. The top 14 of the safe 11 has the rectangular opening 15 cut therein with inclined sides (Fig. 2) into which the lower end of the chute 16 is fitted and secured by the brackets 17 as shown in Figs. 1 and 2. The chute 16 is rectangular in cross-section (Fig. 4) and extends upwardly from the top 14 of the safe 11 obliquely through the sidewall 18 of the bank building as shown in Fig. 1. To the top of the chute 16 is secured the chute head or housing 19 which is embedded in the sidewall 18, the housing 19 being fastened to the top of the chute 16 by the angle bracket 20 (Fig. 2). The housing 19 has the rec-

tangular opening 21 formed in its face plate 22 flush with the outer surface of the side-wall 18, and the face plate 22 carries the horizontally pivotally-mounted entrance door 23 provided with the lock 24 and locking bolt 25 which is adapted to engage the inner edge of the face-plate 22 when projected upwardly as shown in Fig. 2. Any suitable form of key 26 may be used in the lock 24 to actuate the bolt 25 and allow the customer to open the door 23 by lowering same from its locked position (Fig. 2) to its unlocked position (Figs. 1 and 3).

The housing 19 carries the cross-bar 27 on which is journalled the overweighted hopper 28 having the sides 29, bottom 30 and top 31 with the upper opening 32 and lower opening 33 all preferably formed in one piece as shown in Figs. 1-3. The sides 29 each have the outwardly projecting segmental lugs 34 which are adapted to engage and ride in the segmental grooves 35 formed on the inside of the curved back plate 36 secured to the rear of the housing 19 (Figs. 1-3), only one of such lugs 34 and grooves 35 being shown in Fig. 8. This lug 34 and groove 35 arrangement allows the hopper 28 to rock readily on the cross-bar 27, yet serves to prevent any removal of the hopper 28 from the housing 19 because of its lug 34 engagement with groove 35 of the back-plate 36. Pivoted to the lugs 37 formed on the inside of the door 23 are the links 38 (Fig. 3) which are pivotally connected with the pins 39 (only one being shown in Fig. 2) fastened to the hopper sides 29. This construction enables the hopper 28 to be rocked in unison with the rocking movement imparted by the customer to the door 23; Fig. 2 shows the door 23 closed and with the hopper 28 in alinement with the top opening of the chute 16 with its hopper opening 32 effectively closed by the top plate 40 of the housing 19, while in Figs. 1 and 3, the entrance door 23 has been unlocked and lowered to horizontal position, the links 38, acting on the hopper 28 to rock same against gravity with an anti-clockwise movement while the lower opening 33 is at all times closed by the curved surface of the back-plate 36.

In Fig. 1 I have shown the bank sidewall 18 flush with the street sidewalk 41 and the bag or container 42 for money or other valuable provided with a lock 43 in dotted outline about to be deposited in the hopper 28 by the customer of the bank after the door 23 has been lowered and the hopper 28 opened as shown in Fig. 3.

Means are provided for automatically preventing the containers 42 from being lifted from the safe compartment 12 by unauthorized persons opening the door 23 and swinging the hopper 28 to its receiving position, yet at all times allowing the containers 42 to fall by gravity through the chute 16

into such compartment 12. In the embodiment shown a trap comprising a series of spaced-apart yieldable fingers is provided best shown in Figs. 1, 2, 4 and 5. Secured to the inner lower end of the chute 16 is the plate 44 provided with a series of spaced-apart lugs 45 through which extends the cross-shaft 46 (Figs. 4 and 5). Pivotedly mounted to the shaft 46 between the lugs 45 are a series of spaced-apart fingers 47 (nine being shown in Fig. 4) extending transversely from the shaft 46 across the chute 16 and of slightly greater length than the width of the chute 16 as shown in Fig. 2. Coiled about the shaft 46 and bearing against the under side of each finger 47 are the light springs 49 normally urging the fingers 47 upwardly to have the finger tips 50 bear against the under side of the cross-bar 51 secured to the opposite side 52 of the chute 16 (Figs. 2 and 4). Should the cross-bar 51 become displaced or be removed for any reason the finger tips 50 would then press against the side 52 of the chute. It will be seen that these flexible fingers 47 will always yield downwardly to allow the containers 42 to pass freely and downwardly through the chute 16 into the safe compartment 12, yet it is impossible for such containers 42 to be thereafter lifted upwardly from the compartment 12 through the chute 16 because the fingers 47 will bear either against the bar 51 or side 52 to form a grated barrier to the upward passage of the containers 42 through the chute 16.

Means are also provided for automatically closing the lower end of the chute 16 and shutting off the opening 15 leading to the safe compartment 12, should burglars break off the door 23 or face-plate 21 and attempt to remove the hopper 28 from the housing 19, which means are best shown in Figs. 1, 2, 6 and 7. Secured to the safe top 14 adjacent to, and on opposite sides of, the opening 15 are the mutually parallel slotted guide-bars 53 (only one being shown) within which is fitted the rectangular transversely slidable door 54 (Fig. 7) the forward end carrying the rollers 55 adapted to ride in the guide bars 53 (Figs. 2 and 6). Riveted across the under side of the rear end of the door 54 is the cross-bracket 56 to the ends of which are affixed the coil springs 57 with the opposite spring ends fastened to the pins 58 secured within the safe 11. Pivotated to the cross-bar 59 (Figs. 2 and 6) secured to the safe top 14 is the weighted arm 60 of the latch 61, the arm 60 extending forwardly in alignment with the door 54 when the latter is retracted (Fig. 2), and adapted to fall behind the rear edge of the door 54 and dog same (Fig. 6) when the door 54 is advanced, the tip of the arm 60 resting on the guide-bar 53 (Fig. 6). The door 54 is held in its open retracted position (Fig. 2), with the

springs 57 extended under tension, by the forked ends 62 of the rod 63 extending upwardly through the chute 16 (Figs. 1 and 4) and pivoted to the hopper cross-bar 27. The 5 forked ends 62 ride on the pin 64 secured to the side of the chute 16 in the safe top 14 (Fig. 7) and normally extend downwardly across the face of the front edge of the door 54 (Figs. 1 and 2). Should a burglar attempt 10 to remove the hopper 28 from the housing 19 the rod 63 will thereby be pulled upwardly sufficiently to bring the forked ends 62 above the plane of the door 54 (Fig. 6) thereby enabling the springs 57 to pull 15 the door 54 to the left from its Fig. 2 to its Fig. 6 position to shut off the safe compartment 12 from the chute 16. The bracket 56 carries the hand-knob 65 to allow the door to be reset in its normally open position (Fig. 20) after the latch 61 has been moved to raise the latch-arm 60 from its Fig. 6 to its Fig. 2 position so that this weighted arm 60 will rest on the top of the door 54, the latch 61 and knob 65 being actuated from within the 25 safe compartment 12 as shown in Fig. 1.

In operation each bank customer is provided with a key 26 for the door lock 24 and the bank may be provided with a pass key to unlock the individual money container locks 30 43 for which each customer has his key. At any time outside of banking hours the customer of the bank may use this improved chute to deposit his money or other valuables locked in the containers 42 by opening 35 and lowering the entrance door 23 which rocks the hopper 28 by the connecting links 38 against gravity from its Fig. 2 to its receiving position (Figs. 1 and 3). After the container 42 is lodged in the hopper 28 and 40 the customer releases his hold on the door 23, the hopper 28 rocks in a clock-wise direction on the cross-bar 27 which allows the container 42 to fall through the hopper 28 into the chute 16 when alined as shown in 45 Fig. 2. The container 42 passes readily through the flexible fingers 47 which thereafter snap back against the cross-bar 51 and finally falls into the safe compartment 12 through the normally retracted door 54 50 where such containers remain in safe custody until the opening of the bank and proper removal from the safe or vault 11. The operation of the normally-open slide-door 54 upon displacement of the hopper 28 has already 55 been described.

While the construction herein shown embodies my improvements in a preferred form, it will be understood that changes and variations may be made in the structural details without departing from the principles and scope of the invention or sacrificing its chief advantages.

I claim as my invention:

1. In a chute, an oscillatable receiving 65 hopper mounted on the head of the chute,

a normally open closing means for the chute, and an operative connection between said closing means and said hopper to allow said means to close the chute whenever said hopper is displaced from its operative position 70 in the chute.

2. In a chute, an oscillatable receiving hopper, a transversely slideable door to close the chute, means for automatically closing the door in said chute, and an operative connection between said hopper and door for normally maintaining said door-closing means in inoperative condition, but allowing said means automatically to close the door whenever said hopper is displaced from 75 its operative position in the chute.

3. In a chute, an oscillatable receiving hopper, a transversely slideable door to close the chute, means for automatically closing the door in said chute, an operative connection between said hopper and door for normally maintaining said door-closing means in inoperative condition, but allowing said means automatically to close the door whenever said hopper is displaced from 80 its operative position in the chute, and means for automatically locking said door when closed.

4. In a chute, an oscillatable receiving hopper, a transversely slideable door to close the chute, means for automatically closing the door in said chute, an operative connection between said hopper and door for normally maintaining said door-closing means in inoperative condition, but allowing said means automatically to close the door whenever said hopper is displaced from 95 its operative position in the chute, and an over-weighted latch-arm for automatically locking said door when closed.

5. In a chute, an oscillatable receiving 100 hopper, a transversely slideable door to close the chute, means for automatically closing the door in said chute, an operative connection between said hopper and door for normally maintaining said door-closing means in inoperative condition, but allowing said means automatically to close the door whenever said hopper is displaced from 105 its operative position in the chute, means for automatically locking said door when closed, and means for unlocking said last means and resetting said connection to hold the door open.

6. In a chute, an oscillatable receiving 110 hopper, a transversely slideable door to close the chute, means for automatically closing the door in said chute, an operative connection between said hopper and door for normally maintaining said door-closing means in inoperative condition, but allowing said means automatically to close the door whenever said hopper is displaced from 115 its operative position in the chute, an over-weighted latch-arm for automatically locking said door when closed, and manual means for un- 120

125

130

locking said latch-arm and retracting said door to reset said operative connection to hold the door open.

7. In a chute, an oscillatable receiving hopper, a series of spaced-apart, transversely-extending fingers normally held in chute-closing position but yieldingly withdrawn to permit a one-way passage for articles bearing on said fingers within the chute, a door normally slidable to close the lower end of the chute, an operative connection extending between said hopper and door through said fingers for normally maintaining the door in open inoperative position, but allowing the door automatically to close the chute whenever said hopper is displaced from its operative position in the chute.

8. In a chute, an oscillatable receiving hopper, a series of spaced-apart, transversely-extending fingers normally held in chute-closing position but yieldingly withdrawn to permit a one-way passage for articles bearing on said fingers within the chute, a door normally slidable to close the lower end of the chute, an operative connection extending between said hopper and door through said fingers for normally maintaining the door in open inoperative position, but allowing the door automatically to close the chute whenever said hopper is displaced from its operative position in the chute, and means for resetting said door and connection to hold the door in open position.

GEORGE T. BREEN.
